UNITED STATES PATENT OFFICE

108,310

DESIGN FOR LACE

John H. Worrall, New York, N. Y., assignor to Liberty Lace and Netting Works, New York,
N. Y., a corporation of New York

Application December 18, 1937, Serial No. 73,713

Term of patent 3½ years

To all whom it may concern:

Be it known that I, John H. Worrall, a citizen of the United States, residing at No. 2781 Marion Avenue, in the county of Bronx, city of New York, State of New York, have invented a new, original, and ornamental Design for Lace, of which the following is a specification, reference being had to the accompanying drawing forming part thereof.

The drawing shows a face view of a piece of lace embodying the complete design unit, and which design unit is repeated over the surface of the lace.

I claim:—

The ornamental design for lace, substantially as shown and described.

JOHN H. WORRALL.
